TUBE REDUCING MACHINE

Elmer D. Dilling, Las Vegas, Nev., assignor to Titanium Metals Corporation of America, New York, N.Y., a corporation of Delaware

Filed Dec. 7, 1961, Ser. No. 157,745

6 Claims. (Cl. 80—11)

This invention relates to a machine for manufacturing tubing and more particularly to a machine for reducing the wall thickness or internal diameter of tubing or simultaneously reducing the internal diameter and wall thickness thereof.

Conventional tube reducing machines for production of metallic tubing often operate by a swaging action on a starting tube or blank between rolls or dies which rotate or oscillate in a path of travel parallel to the longitudinal axis of the tube. The dies or rolls are grooved to work down the outer diameter of the initial tube. A long tapered mandrel may be used for internal diameter reduction and a series of dies having grooves of appropriate size and curvature are required for producing tubes of desired outside diameter. Such equipment is expensive, heavy and cumbersome and has often failed to produce tubing of desired accuracy of dimension and surface finish.

It is therefore a principal object of this invention to provide an improved tube reducing machine. Another object of this invention is to provide an improved machine capable of reducing the internal diameter of tubing or reducing the wall thickness thereof, or simultaneously reducing internal diameter and wall thickness. A further object of this invention is to provide a tube reducing machine in which the principles of plastic deformation produced by means of a circular working element causing flow in a direction at a right angle to the direction of travel of the circular working element are employed to reduce internal diameter or wall thickness thereof or both internal diameter and wall thickness simultaneously. A still further object of this invention is to provide a tube reducing machine capable of reducing the internal diameter of a tube and equipped with a tool capable of being adjusted to produce a variety of outside diameters of such tube. These and other objects of this invention will be apparent from the following description thereof and from the annexed drawings in which:

FIG. 1 shows a general side view, partially broken out, illustrating a tube reducing machine embodying features of this invention.

FIG. 2 shows an end view of the tool or working head used in the machine of FIG. 1 somewhat enlarged.

FIG. 3 shows a section of the tool of FIG. 2 taken along the line 3—3.

FIG. 4 shows a sectional and enlarged side view of the working rings of the tool of FIGS. 2 and 3 together with a mandrel designed to produce internal diameter reduction in the tube being reduced.

Referring now to FIG. 1, the machine comprises an elongated heavy frame 10 which is supported by pillars 12 and 14 on blocks 16 and 18. The top of frame 10 is provided with horizontal ways 20 on which travel a pair of movable dollies 22 and 24. A central member 26 is provided as part of frame 10 to which are anchored as at 28 the ends of an opposed pair of hydraulic cylinders 30 and 32. The outer ends of the piston rods 34 of hydraulic cylinders 30 and 32 carry rotatable sprockets 36 in whose teeth are engaged the links of chains 38. An upper portion of one of chains 38 is connected to dolly 22 as by heavy bolt 40; the upper end of the other chain 38 being similarly connected to dolly 24 as by bolt 42. The lower ends of chains 38 are anchored to a lower member of frame 10 as at 44. Chains 38 are in effect

2

endless being also carried around inner sprockets 46 which are maintained in fixed, spaced relation to sprockets 36 by bars 48. The axles of sprockets 36 and 46 are supported in a generally horizontal plane by being rotatably mounted on tracks 50.

Mounted on an upper portion of frame 10 and over ways 20 is bearing member 52 which rotatably supports hollow shaft 54. Tool 56, which will hereinafter be described in more detail, is attached as by bolts 57 to one end of shaft 54, and to the other end of shaft 54 is attached bevel gear 58. Meshing with bevel gear 58 is pinion gear 60 which is in turn fixedly mounted on the shaft 62 of electric motor 64.

Securely mounted on dollies 22 and 24 are grip members 66 and 68 respectively. These grip members may be of conventional jamming wedge design, grip member 68 being adapted to grip a workpiece tube 70 being fed into the tool 56, and grip member 66 being adapted to grip a finished tube 72 which constitutes the workpiece tube 20 after passage through and working by tool 56.

Tool 56 is provided with a plurality of working elements in axially spaced relationship, as will be apparent from a more complete description of this element included hereinafter. Workpiece tube 70, during working 25 by tool 56, passes over a mandrel 74 of specific stepped design when reduction of its internal diameter is desired. During working of workpiece tube 70 over mandrel 74, a considerable amount of heat is generated and efficient working action depends at least in part in maintaining 30 a substantially uniform and proper temperature in the portion of the workpiece tube being worked by the tool 56. This is accomplished by provision in mandrel 74 of a pair of openings shown at 76, as will be more clearly seen in FIG. 4, which are in communication with bore 78 35 to form a longitudinal passage. Bore 78 at its other end communicates with pipe 80 which is threaded into an end of mandrel 74 as at 82. Pipe 80 supplies a circulating fluid, preferably a lubricating fluid such as oil. Pipe 80 is connected by swivel joint 84 and union 85 to pipe 40 86 which leads to circulating pump 88, oil being available in reservoir trough 90 to be circulated by pump 88 through pipes 86 and 80, mandrel bore 78 and out of openings 76. Valve 91 is interposed in pipe 86 to control the flow of oil and thermometer 92 is arranged to indicate the temperature of the circulated oil. Electric immersion type heater 94 is placed in trough 90 as shown so that the temperature of circulating oil may be raised initially and afterwards maintained at an elevated temperature. It will be apparent that oil flowing out of openings 76 to the area adjacent the working site and will flow along the inside of tubing 72 and eventually out of the end thereof at 95 from where it will flow down into reservoir trough 90. An additional oil circulating pipe 96 is provided, connected to pipe 86, to supply oil to the 50 outside of workpiece tube 70 at the area where it is being worked by tool 56. This assists in maintaining the workpiece and the working elements of tool 56 at the desired temperature and at the same time provides lubrication for the working action.

The action of hydraulic cylinder 30, which comprises the means for applying tension to an end of workpiece tube 70 to draw it through tool 56, is arranged by provision of four-way valve 97 which controls the directional flow of hydraulic fluid, such as oil, from reservoir 98 pumped under pressure by pump 100 selectively through pipes 102 and 104 which is equipped with gauge 106, or through pipe 103, to either end of cylinder 30. Drain line 110 is provided so that when valve 97 is directing oil into either pipe 104 or 108, oil from the other end of cylinder 30 may be drained therethrough into reservoir 98. Thus, cylinder 30 can, through pressure exerted by its piston rod 34 on its sprocket 36 and its associated

chain 38, apply tension to dolly 22 to draw tube 72 through tool 56.

It is particularly desirable, however, when reducing the internal diameter of tubing to provide back-tension, as it is termed, to workpiece tube 70 so that the tube passing through tool 56 is maintained under longitudinal tension over the working area as well as under additional tension to draw the tube through the tool 56. Means for accomplishing this in the embodiment illustrated include oil pump 114 which also takes its supply from reservoir 98 and which pumps oil through pipe 116 equipped with valve 117 and gauge 118 to the end nearer tool 56 of cylinder 32. By-pass pipe 120 connects to pipe 116 and is equipped with ordinary valve 122 and also pressure relief valve 124 whose outlet is connected by pipe 126 back to reservoir 98. Drain pipe 128 connects the other end of cylinder 32 to reservoir 98 and is provided with valve 129.

In FIG. 1 valve 97 is shown set for operation with workpiece tube 70 being moved through tool 56 to form tube 72 from right to left in the drawing. Pump 100 pumps oil from reservoir 98 to the right hand end of cylinder 30 through pipes 102 and 104. Oil from the left hand end of cylinder 30 drains back to reservoir 98 through pipes 108 and 110. The oil pressure exerting tension through the sprocket chain and dolly on tube 72 is indicated on gauge 106. At the same time pump 114 is maintaining oil pressure through pipe 116 in the left hand end of cylinder 32, and with valve 122 open this pressure is regulated by relief valve 124, the outlet from this valve draining back to reservoir 98 through pipe 126. The pressure in pipe 116 and the end of cylinder 32, acting through its piston rod 34 and its sprocket, chain and dolly, and exerting back-tension on tube blank 70 is indicated on gauge 118. During operation higher pressure is maintained in cylinder 30 (as shown on gauge 106), than in cylinder 32 (as shown on gauge 118) since cylinder 30 must exert draw tension in addition to overcoming the back-tension exerted by cylinder 32.

When it is desired to return the dollies 22 and 24 from left to right (in the drawing) valve 97 is set to selectively transmit oil from pump 100 into the left hand end of cylinder 30 through pipe 108, oil from the right hand end of cylinder 30 draining back through pipes 104 and 102; valve 122 closed and oil under pressure from pump 114 is transmitted to the left hand end of cylinder 32 through pipe 116. Drain line 128 may draw oil into the right hand end of cylinder 32 during travel of its piston from right to left and this will drain back into reservoir 98 during reversal of this movement. Cross pipe 130 is connected between pipe 128 and pipe 116 and equipped with valve 132 normally closed and so arranged that if it is necessary to move the dolly 24 from right to left when the machine is not operating, this can be done by opening valves 132, 122 and 124 and closing valves 117 and 120 to route oil from pump 114 to the right hand end of cylinder 32, oil from the left hand end thereof draining back to reservoir 98 through pipes 120 and 126.

FIGS. 2 and 3 illustrate specifically the tool 56 which is more particularly described and claimed in my pending application Serial No. 78,469, filed December 27, 1960. It comprises a heavy annular frame 134 which is provided with a pair of partial bores 136 and 138 which are drilled or otherwise formed in opposite sides of frame 134. Bores 136 and 138 are eccentric with respect to frame 134 and the eccentricity of these partial bores 136 and 138 is diametrically opposite one to the other. Adjustably mounted in bores 136 and 138 are annular inner frames in the form of rings 140 and 142 which are characterized by eccentric bores 144 and 146. Annular inner frames 140 and 142 may be rotated inside bores 136 and 138 to adjust their relative positions and when set as desired, may be maintained in such adjustment by locking means such as set screws 148 set in from the outer edge of outer frame 134.

Mounted in inner frame bores 144 and 146, as by a

press fit, are bearing assemblies 150 and 152. Mounted in the inner races of bearings 140 and 152 are working rings 154 and 156 and these may also be conveniently assembled to the bearings by a press fit. The inner edges 158 and 160 of working rings 154 and 156 are of blunt cross section partially flattened and adapted to cause plastic deformation of a workpiece against which they are pressed during rotation of tool 56 around such workpiece. As will be seen in the drawings, the internal diameter of rings 154 and 156 is greater than the outside diameter of the workpiece tube 70 so that each of the inner edges 158 and 160 thereof contact and work the metal of the workpiece tube 70 only over a portion of one side thereof at any one time, the contacted portion progressively moving around the circumference of the workpiece tube 70 as the tool 56 rotates around it.

It will be seen that the working elements, that is rings 154 and 156, are not aligned to act on the workpiece 70 in the same plane but are arranged in side by side relationship. Thus these working elements are spaced longitudinally along the workpiece (and also with respect to mandrel 74), and are referred to as axially spaced with respect to each other. It will additionally be understood that in a compact tool design the spacing relationship between the sides of the working elements may be very close, but their inner edges, as 158 and 160 of rings 154 and 156, will ordinarily be somewhat further spaced apart.

Flat cover rings 162 are provided to maintain inner frames 140 and 142, bearings 150 and 152, and working rings 154 and 156 in their proper adjusted relationship. These are firmly attached to opposite sides of outer frame 134 by means of bolts 164.

Heavy bolts 57 pass through cover rings 162 and outer frame 134 to fasten the tool 56 as an integral assembly fixedly to the end of hollow shaft 54.

Referring now to FIG. 4 the mandrel 74 for producing reduction of internal diameter of a workpiece such as workpiece tube 70, is characterized by being stepped, with shoulders or risers as at 166 and at 168. These shoulders 166 and 168 produce mandrel diameter reduction corresponding to the desired reduction in internal diameter of the workpiece tube 70 and are longitudinally spaced along mandrel 74 to correspond with the spacing between working edges 158 and 160 respectively of working rings 154 and 156. Working edges 158 and 160 continuously work metal of workpiece tube 70 down onto the mandrel steps following shoulders 166 and 168 and by appropriate setting of rings 154 and 156 by their frames 144 and 146 in tool 56, can also effect a reduction in wall thickness of workpiece tube 70.

In operation of the machine, the working rings 154 and 156 of tool 56 are first adjusted in their inner frames 140 and 142 to provide the required reduction in tube outside diameter. A workpiece tube 70 is pointed (by any convenient and known method) and the pointed end passed through tool 56 and gripped by grip 66 on dolly 22. The feed end of workpiece tube 70 is gripped by grip 68 on dolly 24 at any convenient point along its length. A mandrel 74, of design to accomplish the required inside diameter reduction, is threaded onto pipe 80 as at 82 and inserted into the workpiece tube 70 so that its shoulders 166 and 168 are aligned with corresponding edges 158 and 160 of working rings 154 and 156. Connection of pipe 80 with swivel 84 to pipe 86 is conveniently made by union 85. Heater 94 is then turned on to heat the oil in reservoir trough 90 and pump 88 is started to circulate hot oil through the mandrel 74; and also to the outside surface of the workpiece tube 70 and working rings 154 and 156 through pipe 96. When the temperature of these elements has been sufficiently raised, as indicated by a circulating oil temperature of preferably between 200° and 300° F., motor 64 is started to rotate tool 56 around the workpiece tube 70. Pump 100 is started to actuate hydraulic cylinder 30 to draw the finished tube 72 through tool 56 and pump 114 is operated

and relief valve 124 set to maintain back-tension on the workpiece tube 70. The setting of the hydraulic system valves during operation is as shown in FIG. 1 of the drawings and as previously described. During operation the circulating oil is maintained at elevated temperature by adjustment of heater 94 and valve 91.

As the workpiece tube 70 is drawn through the tool 56 the working rings 154 and 156 progressively work the metal of the workpiece tube 70 by plastic deformation causing flow in a direction at a right angle to the direction of travel of working rings 154 and 156. The working action produces a reduced tube 72 corresponding in internal diameter to the diameter of the small end of the mandrel 74 and of wall thickness determined by the spacing between the edge 158 of working ring 154 and the outside surface of the small end of the mandrel 74 aligned with it.

After reduction of workpiece tube 70 over its length (except for a necessary gripping portion at each end) tool 56 is stopped, oil circulating pump 83 is shut down, hydraulic system pumps 100 and 114 are shut down, mandrel 74 is removed by separating pipe 80 and swivel 84 from pipe 86 at union 85, and the ends of the workpiece tube 70 and finished tube 72 are removed respectively from grips 68 and 66. Finished tube 72 is then withdrawn through tool 56; and may be further processed by separation of point and workpiece stub ends and any further finishing desired. The dollies 22 and 24 are then repositioned and the operation is repeated to reduce another length of tube.

The speed of tool 56 rotation and the settings to produce draw and back-tension and other operating factors, will necessarily be adjusted with regard to the size of the tubing, the degree of reduction accomplished and the tubing material. As an example, a workpiece tube 70 of commercially pure titanium tubing of 1.25 inches outside diameter and 1.07 inches inside diameter was reduced to produce a tube of 0.920 inch outside diameter and 0.780 inch inside diameter. A machine of the type illustrated in FIG. 1 was used with the tool 56 rotated at 550 r.p.m. and the circulating oil maintained at a uniform temperature of about 200° F. Relief valve 124 was set to show a pressure on gauge 118 of 50 p.s.i. which produced a back-tension calculated from previous calibration of 6,100 p.s.i. over the workpiece tube wall section area, while cylinder 30 was pulling the tube through the rotating tool 56 at a draw speed of 6 inches of workpiece feed tube length per minute, a pressure of 85 p.s.i. showing on gauge 105.

Control of the temperature of mandrel 74 appears to be important for efficient production of good finish tubing. The working action of rings 154 and 156 on workpiece tube 70 produces a considerable amount of heat and as the reduction proceeds along a length of workpiece tube the mandrel and the workpiece will become subject to local overheating unless provisions for circulating oil, or other fluid, as hereinbefore described. Should the mandrel, and more particularly of course, the workpiece tube in contact with it, become overheated the workpiece tube will become susceptible to fracture under the working rings 154 and 156 due largely to the tension applied to the tube over the working area. On the other hand, at the beginning of an operation with the mandrel cold, excessive work hardening of the workpiece tube 70 can cause embrittlement resulting in cracks in the workpiece and sometimes fracture. For these reasons at the start of a tube reducing operation it is advantageous to heat the oil circulated to mandrel 74 to bring it and the workpiece tube 70 quickly up to a desirable operating temperature, and after the operator has been running, to shut off or cut down the current to the heater and circulate the oil to prevent overheating but still maintaining it at an elevated temperature. It has been found advantageous to maintain the circulating oil at a substantially uniform elevated temperature, and this may be up to sev-

eral hundred degrees Fahrenheit. When reducing titanium tubing, for example, an oil temperature of between 200° F. and 300° F. has been found to provide good operating conditions. If necessary or desirable, conventional cooling coils, circulating water, may be employed in the oil circulating system, but ordinarily adequate control of flow and temperature may be obtained by valve 91 and heater 94.

Provision of the swivel joint 84 between pipes 80 and 86 to allow pipe 80 to freely rotate, is important to produce tubing with superior inside surface finish. As the machine operates tool 56 is revolved around workpiece tube 70, but this workpiece tube 70 and the reduced tubing 72 does not rotate but simply travels through tool 56 with its length increased corresponding to the reduction performed. Mandrel 74 stays in the same longitudinal position relative to working rings 154 and 156 but amazingly, and for reasons not completely understood, tends to rotate in a direction opposite to the direction of rotation of tool 56. This tendency for mandrel 74 to rotate is apparently very strong, and if mandrel 74 is fixedly mounted and restrained, the internal surface of workpiece tube 70 can become scuffed or rough. However, when mandrel 74 is connected as described and shown, being substantially floating and freely rotatable in tube 70, its tendency to rotate is uninhibited and it will in fact rotate continuously, but as explained above in a direction opposite to that of tool 56. It has been found, however, that when the mandrel is allowed to freely rotate, sliding or scuffing of the internal surface of the workpiece 70 on the surface of mandrel 74 is eliminated and a smooth, even, internal surface finish results.

It is significant that the machine of this invention produces internal diameter reduction alone or combined with wall thickness reduction by a process in which the metal working elements travel around their axes which are generally parallel to the longitudinal axis of the tube. The principle involved is therefore not one of rolling in the generally accepted sense, or of swaging, but results in metal working and flow in a direction principally at right angles to the path of travel of the tool working edge. As the rings 154 and 156 travel around the workpiece, metal is displaced laterally out from under their working edges.

Provision of means for applying back-tension to the workpiece tube is particularly important during reduction of inside diameter of tubing and it is also useful to produce improved operation during reduction of wall thickness. When reducing inside diameter or wall thickness there appears to be some tendency for metal to pile up somewhat ahead of the working rings as they travel around the workpiece and to form a ridge between the working areas. Application of back-tension under these conditions relieves this tendency and the metal flows smoothly out at lengthwise of the tube and right angles to the diameter plane of the working rings. It is interesting that back-tension which is applied longitudinally along the tube length, effectively reduces or stops metal tending to flow or pile up ahead of the working rings in a direction at right angles to the length of the tube and of course, the direction of application of the back tension. The back-tension should be maintained during operation at not more than about 50% of the yield strength of the material of which the workpiece is constituted, the yield strength being determined at room temperature by conventional and known methods. The pressure shown on pressure gauge 118, as will be apparent, is applied as a force over the area of the piston head in cylinder 32 and can be calculated to indicate the back tension in pounds per square inch applied to the original cross sectional area of the wall of the workpiece 70. Alternatively the gauge may be calibrated for the same purpose by arranging a strain gauge applied to a workpiece tube 70 and plotting tension forces actually obtained for various gauge pressures.

The machine of this invention is useful for reducing welded tubing. The welded area will be found to be

worked down by the action of tool 56 so that a uniform wall thickness tube is produced as a product. In fact if the machine is set to produce a substantial reduction in wall thickness, area or sink, it is sometimes difficult, after reduction, to recognize the previously welded seam.

A variety of sizes of tubing using a range of workpiece tube sizes may be produced by the machine of this invention. The working rings of tool 56 may be adjusted as described within limits to provide the desired outside diameter of the finished tubing, with the individual working rings set to produce the desired reduction effect. The mandrel must be designed for the specific internal diameter reduction desired except in the case where wall reduction only is accomplished, in which case the mandrel will be a uniform cylindrical piece. When arranging the mandrel for internal diameter reduction it is advantageous to provide steps that will accomplish about one half the total reduction under each working ring with the diameter of the mandrel at its small end being the size desired as the internal diameter of the reduced tube. The angle of the shoulders between steps is preferably from 10 to 40 degrees to the longitudinal axis of the mandrel and the nose or working edge of the corresponding working ring should generally conform to the configuration of the mandrel as it reduces over the shoulder and down to the following smaller diameter step.

The machine of this invention has been found to produce a useful degree of correction of eccentricity in the workpiece tube. The reason for this is not precisely known but it is postulated that the axially spaced working rings working over the mandrel, which is essentially floating in the workpiece tube, tend to work out the metal to produce a uniform wall thickness in the finished tube. Since the mandrel and workpiece floats between the working rings, the forces exerted by the individual working rings are essentially equal. It is significant that reductions of wall thickness up to 65% can be obtained simultaneously with reduction in internal diameter (sink), and at the same time an improvement in concentricity can be imparted to the tube.

This application is a continuation-in-part of my co-pending application Serial No. 78,469, filed December 27, 1960.

I claim:

1. A tube reducing machine comprising:

(a) a frame,

(b) a tool rotatably mounted on said frame, said tool having a plurality of circular working elements in axially spaced relationship and with their axes parallel to the axis of a metal workpiece tube passing therethrough,

(c) means for rotating said tool around said metal workpiece tube,

(d) a stepped mandrel having a plurality of shoulders disposed inside said workpiece tube, and

(e) means for applying tension to an end of said workpiece tube to draw it through said tool,

each of said shoulders of said mandrel being aligned with one of the working elements of said tool, an edge of each of said working elements being adapted to cause plastic deformation of the metal of said workpiece tube onto a step of said mandrel and following the shoulder of said mandrel with which each is aligned, to produce reduction of the internal diameter of said workpiece tubing.

2. A tube reducing machine comprising:

(a) a frame,

(b) a tool rotatably mounted on said frame, said tool having a plurality of working rings in side by side relationship and with their axes parallel to the axis of a metal workpiece tube passing therethrough,

(c) means for rotating said tool around said metal workpiece tube,

(d) a stepped mandrel having a plurality of shoulders disposed inside said workpiece tube, and

5 (e) means for applying tension to an end of said workpiece tube to draw it through said tool, each of said shoulders of said mandrel being aligned with the inner edge of one of said working rings of said tool, the said edge of each of said working rings being adapted to cause plastic deformation of the metal of said workpiece tube onto a step of said mandrel and following the shoulder of said mandrel with which each is aligned, to produce reduction of the internal diameter of said workpiece tubing.

10 3. A tube reducing machine comprising:

(a) a frame,

(b) a tool rotatably mounted on said frame, said tool having a pair of working rings in side by side relationship and with their axes parallel to the axis of a metal workpiece tube passing therethrough,

(c) means for rotating said tool around said metal workpiece tube,

(d) a stepped mandrel having a pair of shoulders disposed inside said workpiece tube, and

(e) means for applying tension to an end of said workpiece tube to draw it through said tool,

15 each of said shoulders of said mandrel being aligned with the inner edge of one of said working rings of said tool, the said edge of each of said working rings being adapted to cause plastic deformation of the metal of said workpiece tube onto a step of said mandrel and following the shoulder of said mandrel with which each is aligned, to produce reduction of the internal diameter of said workpiece tubing.

20 4. A tube reducing machine comprising:

(a) a frame,

(b) a tool rotatably mounted on said frame, said tool having a plurality of working rings in side by side relationship and with their axes parallel to the axis of a metal workpiece tube passing therethrough,

(c) means for rotating said tool around said metal workpiece tube,

(d) a mandrel disposed within said workpiece tube and aligned with said working rings of said tool,

(e) means for applying tension to one end of said workpiece tube to draw it through said tool, and

(f) means for applying back tension to the other end of said workpiece tube,

25 the inner edges of said working rings being adapted to cause plastic deformation of the metal of said workpiece tube and displacement thereof in a direction at a right angle to the direction of travel of said working rings around the circumference of said metal workpiece tube.

30 5. A tube reducing machine comprising:

(a) a frame,

(b) a tool rotatably mounted on said frame, said tool having a pair of working rings in side by side relationship and with their axes parallel to the axis of a metal workpiece tube passing therethrough,

(c) means for rotating said tool around said metal workpiece tube,

(d) a mandrel disposed within said workpiece tube and aligned with said working rings of said tool,

(e) means for applying tension to one end of said workpiece tube to draw it through said tool, and

(f) means for applying back tension to the other end of said workpiece tube,

35 the inner edges of said working rings being adapted to cause plastic deformation of the metal of said workpiece tube and displacement thereof in a direction at a right angle to the direction of travel of said working rings around the circumference of said metal workpiece tube.

40 6. A tube reducing machine comprising: a frame, a tool rotatably mounted on said frame, said tool having a plurality of working rings in side by side relationship and with their axes parallel to the axis of a metal workpiece tube passing therethrough, means for rotating said tool around said metal workpiece tube, a mandrel dis-

posed within said workpiece tube and aligned with said working rings of said tool, and means for applying tension to one end of said workpiece tube to draw it through said tool, the inner edges of said working rings being adapted to cause plastic deformation of the metal of said workpiece tube and displacement thereof in a direction at a right angle to the direction of travel of said working rings around the circumference of said metal workpiece tube.
